HEATING STOVE

Original Filed Jan. 31, 1928

INVENTOR.

G. F. Reznor
BY
F. N. Barber
ATTORNEY.

UNITED STATES PATENT OFFICE.

GEORGE FOSTER REZNOR, OF MERCER, PENNSYLVANIA.

HEATING STOVE.

Application filed January 31, 1928, Serial No. 250,783. Renewed March 1, 1929.

My invention relates to heating stoves of the radiant burner type.

One object of this invention is to provide a novel means for supporting the burner. Another object is to provide means for permitting expansion of the fire-clay back of the stove without straining or damaging any of the stove parts. Another object is to produce a novel means for supporting the radiants. Another object is to provide a unitary means carried by the sides of the stove for supporting the said back and radiant support, holding in place the said back and support, and providing supports for the said means for permitting expansion of the said back.

Referring to the accompanying drawing, Fig. 1 is a horizontal section of the rear part of my stove, parts being broken away; Fig. 2, a rear elevation of a portion of the stove, parts being omitted and broken away; Fig. 3, a top plan view of one end of the radiant support; and Fig. 4, a section on the line 4—4 on Fig. 3.

On the drawing, 10 and 11 designate the metallic vertical side members of the stove, each having a horizontal ledge or shelf 12 on its inner face, the ledges lying opposite each other. The burner 13 reaches from one side member to the other and may be of any suitable type, such, for example, as that shown in my application, Serial No. 165,311, filed February 2, 1927. The ends of the burners lie beneath the ledges 12 and in contact therewith, screws 14 securing the ends of the burners to the ledges. The ledges are cast in one piece with the respective sides 10 and 11.

In front of the ledges and cast integrally therewith and with the sides 10 and 11 are the thin vertical ribs or flanges 15 projecting toward each other.

16 is the radiant support composed of sheet metal and having at its ends the slots 17 which receive the said flanges 15 to keep the radiant support from backward and forward movements. The ends of the support rest upon the ledges 12. The support has near each end a finger or rest 18 integral therewith and projecting downwardly and rearwardly so as to rest on the upper face of the burner 13 to prevent the support from rotation or tilting toward the rear when the radiants rest thereon. As shown in Fig. 1, the forward side of the radiants (one marked 19 being shown) rest on the rear portion of the support 16 which might turn more or less but for the fingers 18.

The support 16 has a number of upstanding

projections or radiant centering and holding lugs 20 and 21, arranged in rear and front rows respectively. The lugs 20 and 21 are arranged in pairs, the members 20 of the pairs standing the forward angles in the radiants while the members 21 of the pairs engage the outer or front faces of the radiants just opposite the members 20, whereby the radiants are held from movement in all horizontal directions.

The rear face of the radiants contact with the front face of the back wall 23 made of any suitable refractory material, such as fire clay. The back wall 23 rests upon the ledges 12 and on the ends of the radiant support 16 just at the rear of the flanges 15, whereby the said support is held down firmly. The said wall is hollowed out in front to receive the radiants while its end portions 24 extend forwardly and stand spaced from the stove sides 10 and 11 while the front edges of the portions 24 preferably engage the rear faces of the flanges 15.

A flue 25 is provided behind the wall 23 by the vertical metal plate 26 having its intermediate portions extending rearwardly beyond the wall 23, while its end portions extend forwardly where they are provided with flanges 27 resting against the outer face of the wall 23 near its ends. The rear faces of the sides 10 and 11 have secured thereto by screws 28 the vertical metal strips or plates 29 having resilient fingers 30 overlapping the rear faces of the flanges 27 of the plate 26, and contacting therewith to hold the back wall 23 in place and provide means whereby the back wall may expand without distorting any part of the stove except the fingers 30 which will yield to allow expansion and follow up the back when it contracts.

I claim—

1. In a stove, upstanding sides, shelves on the opposing faces of the sides, a burner attached to the shelves, a refractory back wall having its ends resting on the shelves, flanges carried by the forward edges of the sides and projecting toward each other and forming a front abutment for the said ends of the back wall.

2. In a stove, upstanding sides, shelves on the opposing faces of the sides, a burner attached to the shelves, a refractory back wall having its ends resting on the shelves, flanges carried by the forward edges of the sides and projecting toward each other and forming a front abutment for the said ends of the back

wall, in combination with a radiant support having its ends forked and receiving between the members thereof the said flanges, the ends of the radiant support resting on the shelves.

3. In a stove, upstanding sides, shelves on the opposing faces of the sides, a burner attached to the shelves, a refractory back wall having its ends resting on the shelves, flanges carried by the forward edges of the sides and projecting toward each other and forming a front abutment for the said ends of the back wall, in combination with a radiant support having its ends forked and receiving between the members thereof the said flanges, the ends of the radiant support resting on the shelves and beneath the said ends of the back wall.

4. In a stove, upstanding sides, a burner between the sides, a refractory back wall back of the burner, and means confining the front and back faces of the back wall, the means confining one of the said faces being yieldable horizontally whereby the horizontal expansion of the back wall is permitted while it is held firmly in place.

5. In a stove, upstanding sides, a burner between the sides, a refractory back wall back of the burner, means confining the front of the back wall, and yieldable means confining the back of the back wall and permitting horizontal expansion thereof.

6. In a stove, upstanding sides, a burner between the sides, a refractory back wall back of the burner, means confining the front of the back wall, and yieldable means confining

the back of the back wall and permitting horizontal expansion thereof, in combination with a plate behind the back wall and spaced therefrom at its intermediate portions and clamped at its ends between the back wall and the said yieldable means.

7. In a stove, upstanding sides, a burner between the sides, a radiant support carried by the sides in front of the burner, means on its rear portion for supporting and holding radiants in fixed position, a refractory back wall to support the rear side of the radiants, and rearwardly extending legs carried by the radiant support and resting on the burner to prevent the said support from tilting rearwardly.

8. In a stove, sides, a burner connected between the sides, a hollow angular radiant, a sheet metal support for the radiant, and upstanding lugs carried by the radiant support, some of the lugs standing in the forward interior angles of the radiant and others of the lugs engaging the front face of the radiant.

9. In a stove, upstanding sides, shelves on the opposing faces of the sides, a burner attached to the shelves, a refractory back wall having its ends resting on the shelves, flanges carried by the forward edges of the sides and projecting toward each other and forming a front abutment for the said ends of the back wall, in combination with a radiant support.

In testimony whereof, I hereunto affix my signature.

GEORGE FOSTER REZNOR.
